CLAIM

The ornamental design for a casing for a motor monitoring device, as shown and described.

DESCRIPTION

FIG. 1 is a perspective view of a casing for a motor monitoring device showing the new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a perspective view thereof where the casing for the motor monitoring device is shown positioned on a motor. The broken line showing of FIG. 8 is for the purpose of illustrating environmental structure and forms no part of the claimed design.
